UNITED STATES PATENT OFFICE.

FORREST NAGLER, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

HYDRAULIC INSTALLATION.

Application filed March 26, 1923. Serial No. 627,591.

To all whom it may concern:

Be it known that FORREST NAGLER, a citizen of the United States, residing at Wauwatosa, in the county of Milwaukee and State of Wisconsin, has invented a certain new and useful Hydraulic Installation, of which the following is a specification.

This invention relates in general to improvements in the construction and operation of hydraulic installations, and relates more specifically to instrumentalities for improving the operation of hydraulic turbine or pump units operable under relatively low heads.

A general object of the present invention is to provide simple and efficient means for improving the operation of hydraulic installations.

It has been found difficult in hydraulic power installations operable under relatively low heads, and especially in so called siphon settings wherein at least a portion of the water delivered to the turbine rotor is caused to flow above the head water level, to maintain the inlet conduit completely filled with water. In most installations of this kind it is necessary to provide special pumping auxiliaries for the purpose of removing air from sealed pockets of the inlet conduit, in order to establish full admission of water to the rotor and to eliminate excessive entry of air. The present invention contemplates provision of simple means automatically operable by the normal turbine structure, for effectively filling the inlet conduit of a turbine embodying a siphon setting, and for maintaining the inlet conduit filled during normal operation of the turbine.

While the structure for admitting air from an external source to the central portion of a vortex of liquid which is utilized to operate a hydraulic turbine, is herein disclosed, similarly functioning structure forms part of what is claimed in a copending application Ser. No. 627,042, filed Mar. 23, 1923.

A clear conception of several embodiments of the present invention and of the operation of apparatus constructed in accordance therewith, may be had by referring to the drawings accompanying and forming a part of this specification in which like reference characters designate the same or similar parts in the various views.

Fig. 1 is a central vertical section through a low head hydraulic turbine installation

embodying a rotor of the axial flow type having high specific or characteristic speed.

Fig. 2 is a central vertical section through a low head hydraulic turbine installation embodying a rotor of the Francis type.

Fig. 3 is a fragmentary sectional view of a novel form of air ejecting device applicable to either of the installations disclosed in Figs. 1 and 2.

Referring specifically to Fig. 1, the hydraulic turbine installation has a siphon setting and comprises in general an axial flow impeller or rotor 2 direct connected to the rotor of a generator 10 by means of a vertical main shaft 9; a penstock 3 for supplying water to the turbine rotor 2 through a spiral inlet conduit 11 and through suitable flow control mechanism; and a tail-race 8 communicating with the discharge side of the turbine rotor 2 through a flow decelerating device or draft tube 7. The spiral inlet conduit 11 is formed directly within the concrete turbine setting 14 and extends a considerable distance above the normal head water level in the penstock 3. The turbine inlet mechanism for controlling the delivery of water from the spiral conduit 11 to the rotor 2, comprises an annular series of stationary guide vanes 4 forming a speed ring structure and serving as a support for the generator 10; an annular series of movable flow control guide vanes 5 adjustable about vertical axes by means of adjusting mechanism 15; and an annular vane free transition space 6 for changing the direction of advancement of the whirling mass of water delivered from the guide vanes 5 from radial to axial. The rotor 2 is located at the lower end of the transition space 6 and within the upper interior portion of a hollow pier 23 the lower inner portion of which forms the draft tube 7. The uppermost extremity of the spiral inlet conduit 11 is connected with the inner or central portion of the transition space 6 by means of a pipe 12 having a control valve 13 therein capable of varying the cross-sectional area of the pipe 12 and also capable of admitting air to the conduit 11.

Referring specifically to Fig. 2, the hydraulic turbine installation has a siphon setting and comprises in general a Francis type runner or rotor 20 direct connected to the rotor of a generator 17 by means of a vertical main shaft 16; a penstock 3 for supplying water to the turbine rotor 20 through

a spiral inlet conduit 11 and through suitable flow control mechanism; and a tail-race 8 communicating with the discharge side of the turbine rotor 20 through a flow decelerating device or draft tube 7. The spiral inlet conduit 11 is formed directly within the concrete turbine setting 14 and extends a considerable distance above the normal head water level in the penstock 3. The turbine inlet gate mechanism for controlling the delivery of water from the spiral conduit 11 to the rotor 20 comprises an annular series of movable flow control guide vanes 5 adjustable about vertical axes by means adjusting mechanism not shown. The rotor 20 is of the inward-inlet axial-discharge flow type and extends downwardly into the interior of a hollow pier 28 the lower inner portion of which forms the draft tube 7. The uppermost extremity of the spiral inlet conduit 11 is connected with the interior of the upper turbine casing by means of a pipe 18 having a three way control valve 19 therein. The interior of the upper casing portion is provided with passages 21 communicating with the interior of the rotor 20 and of the draft tube 7 by means of a series of ports 22.

Referring specifically to Fig. 3, the uppermost extremity of the spiral inlet conduit 11 is connected with a pipe 12 such as shown in Fig. 1, or with a pipe 18 such as shown in Fig. 2, by means of an air discharge nozzle 24 the lower extremity of which forms a seating for a ball float valve 25. The ball float valve 25 is retained in proximity to the seating 24 by means of a suitable cage, and is adapted to be elevated into engagement with the seating 24 by the water rising 40 within the conduit 11.

During normal operation of the unit disclosed in Fig. 1, the inlet guide vanes 5 are adjusted by manipulation of the mechanism 15 to admit water from the penstock 3 to the transition space 6. The guide vanes 5 produce a vortex of whirling water within the transition space 6, this vortex of water being delivered to the rotor 2 and imparting rotation to the turbine rotor, to the main shaft 9 and to the rotor of the generator 10. The water delivered from the rotor 2 passes through the draft tube 7 to the tail-race 8. The whirling vortex of water passing through the transition space 6 creates a zone of reduced pressure along the inner wall of the transition space 6, this zone of reduced pressure extending from the upper delivery edges of the guide vanes 5 and into the central portion of the draft tube 7. By virtue of the existence of this zone of reduced pressure within the transition space 6, and with the valve 13 set to produce a continuous passage through the pipe 12, any air confined within the upper portion of the spiral inlet conduit 11

is immediately withdrawn and the water from the penstock 3 rises into the uppermost portion of the conduit 11. With the structure shown in Fig. 1, the flow of air through the pipe 12 will be followed by the delivery of a small quantity of water direct from the conduit 11 through the pipe 12 to the transition space 6, but the delivery of this water through passages other than those between the guide vanes 5 is not objectionable since this water must subsequently pass through the rotor 2. The control valve 13 normally serves to vary the cross-sectional area of the air ejecting conduit, and may also be formed to permit entry of air to the conduit 11 when it is desired to break the vacuum in the conduit 11. The air and water thus delivered from the upper portion of the inlet conduit 11 into the transition space 6 merges with the whirling liquid passing the guide vanes 5 and passes through the runner 2 and draft tube 7 to the tail-race 8.

During normal operation of the unit disclosed in Fig. 2, the inlet guide vanes 5 are adjusted to admit water from the penstock 3 to the rotor 20, in any convenient manner. The guide vanes 5 produce a vortex of whirling water which is delivered through the rotor 20 and imparts rotation to the shaft 16 and to the rotor of the generator 17. The water delivered from the rotor 20 advances as a vortex of whirling liquid through the draft tube 7 and is eventually delivered to the tail-race 8. The whirling vortex of water creates a zone of reduced pressure adjacent to the axis of the installation, this zone of reduced pressure extending from the upper delivery edges of the guide vanes 5 and downwardly into the central portion of the draft tube 7. By virtue of the existence of this zone of reduced pressure adjacent to the central vertical axis of the unit, and with the control valve 19 properly set, any air which may be confined within the upper portion of the spiral inlet conduit 11 is withdrawn and the water from the penstock 3 rises into the uppermost portion of the spiral conduit 11. With the structure shown in Fig. 2, the flow of air through the pipe 19 will be followed by the delivery of small quantities of water direct from the conduit 11 to the draft tube 7, but such delivery of water is negligible as compared to the total amount passing through the rotor 20. The control valve 19 normally serves to vary the cross-sectional area of the air ejecting conduit or pipe 18, and may also be formed to admit air to the conduit 11 in order to break the vacuum therein.

With the automatic air control valve disclosed in Fig. 3, the rising water upon reaching the ball float valve 25 automatically raises this valve and seats the same upon the

seating 24 thereby preventing escape of water through the air ejector pipe 12 or 18 after the water has completely filled the conduit 11 and the air has been withdrawn therefrom. When more air accumulates in the upper portion of the conduit 11 the water level therein drops, thereby permitting the ball float valve 25 to move away from the seating 24 and allowing the air to escape from the conduit 11. When the unit has been stopped, the vacuum in the conduit 11 may readily be destroyed by proper adjustment of the control valve 13, 19.

It will thus be noted that with the present invention the normal turbine structure is utilized to automatically prevent undesirable pocketing of air in the sealed portion of the conduit 11 located above the turbine inlet gate mechanism and above the head water level. By thus completely filling the spiral inlet conduit 11, a sufficient supply of liquid to all portions of the turbine gate mechanism is assured and entry of excessive quantities of air to the rotor is eliminated. By utilizing the air control valve disclosed in Fig. 3, waste of water is positively avoided and the air ejector passage is automatically closed when no air is available in the confined portion of the conduit 11. The air ejector is conveniently applicable to existing installations as well as to new units, and does not interfere with any portion of the turbine mechanism.

It should be understood that it is not desired to limit the present invention to the exact details of construction and to the precise mode of operation herein described, for various modifications within the scope of the claims may occur to persons skilled in the art.

It is claimed and desired to secure by Letters Patent:

1. In a hydraulic machine, a rotor operable in a vortex of liquid, means forming a sealed supply chamber segregated from and extending around the axis of said rotor, and conduit means connecting the upper portion of said chamber directly with the central portion of said vortex.

2. In a hydraulic machine, a rotor operable in a vortex of liquid, means forming a sealed supply chamber surrounding the axis of and extending above said rotor, and conduit means connecting the upper portion of said chamber directly with said vortex adjacent to the axis of said rotor.

3. In a hydraulic machine, a rotor operable in a vortex of liquid, means for controlling the flow of liquid to said rotor, means forming a sealed supply chamber segregated from said rotor and extending above said controlling means, and conduit means connecting said chamber directly with the central portion of said vortex without obstructing the flow of liquid.

4. In a hydraulic machine, a rotor operable in a liquid vortex having a zone of reduced pressure adjacent the rotor axis, gate mechanism for producing said vortex and for controlling the flow of liquid to said rotor, means forming a liquid supply conduit communicating with the inlet opening of said mechanism and having a sealed portion extending above the top of the gate opening, and conduit means connecting said sealed conduit portion directly with said zone of reduced pressure without obstructing the flow of liquid in said vortex.

5. In a hydraulic machine, a rotor operable in a liquid vortex having a zone of reduced pressure adjacent to the rotor axis, an annular series of guide vanes for producing said vortex, means forming a liquid supply conduit communicating with the spaces between said guide vanes and extending above said spaces to form a sealed chamber, and conduit means directly connecting said chamber and said zone without obstructing the flow of liquid in said vortex.

6. In a hydraulic machine, a rotor operable in a liquid vortex having a zone of reduced pressure adjacent to the rotor axis, an annular series of guide vanes for producing said vortex and for controlling the flow of liquid to said rotor, means forming a liquid supply conduit communicating with the spaces between said guide vanes and having a sealed portion extending above the top of said spaces, and conduit means connecting said sealed conduit portion directly with said zone of reduced pressure without obstructing the flow of liquid in said vortex.

7. In a hydraulic machine, a rotor operable in a vortex of liquid, a source of liquid supply, means forming a sealed supply chamber segregated from and located above the level of liquid in said source, and conduit means connecting the upper portion of said chamber directly with the central portion of said vortex without obstructing the flow of liquid therein.

8. In a hydraulic machine, a rotor operable in a vortex of liquid, a source of liquid supply, means for controlling the flow of liquid from said source to said rotor, means forming a sealed supply chamber surrounding said rotor and located above the level of the liquid in said source, and conduit means connecting the upper portion of said chamber directly with the central portion of said vortex without obstructing the flow of liquid therein.

9. In a hydraulic machine, a rotor operable in a liquid vortex having a zone of reduced pressure adjacent the vortex axis, a source of liquid supply, gate mechanism for producing said vortex and for controlling the flow of liquid from said source to said rotor, means forming a liquid supply con-

duit connecting said source and said mechanism and having a sealed portion extending above the level of liquid in said source, and conduit means connecting the upper part of said sealed conduit portion directly with said zone of reduced pressure without obstructing the flow of liquid in said vortex.

10. In a hydraulic machine, a rotor operable in a vortex of liquid, means forming a sealed chamber segregated from said rotor, conduit means connecting said chamber directly with the central portion of said vortex without obstructing the flow of liquid therein, and means for automatically closing said conduit means.

11. In a hydraulic machine, a rotor operable in a vortex of liquid, means for controlling the flow of liquid to said rotor, means forming a sealed chamber segregated from said rotor and located above said flow controlling means, conduit means connecting said chamber directly with the central portion of said vortex without obstructing the flow of liquid therein, and means for automatically closing said conduit means when the air has been removed from said chamber.

12. In a hydraulic machine, a rotor operable in a liquid vortex having a zone of reduced pressure adjacent the rotor axis, a source of water supply, gate mechanism for producing said vortex and for controlling the flow of liquid from said source to said rotor, means forming a liquid supply conduit connecting said source with said mech-

anism and having a sealed portion extending above the level of the liquid in said source, conduit means connecting the upper part of said sealed conduit portion directly with said zone of reduced pressure, and means for automatically closing said conduit means when the air has been removed from said sealed conduit portion.

13. In a hydraulic machine, a rotor operable in a vortex of liquid, means forming a sealed chamber segregated from said rotor, conduit means connecting the upper portion of said chamber directly with the central portion of said vortex to produce a vacuum in said chamber, and means for breaking said vacuum.

14. In a hydraulic machine, a single rotor operable in a vortex of liquid having a vertical central axis, a spiral inlet conduit surrounding said axis and having a sealed portion located above said rotor, and conduit means connecting the highest portion of said inlet conduit directly with the central portion of said vortex.

15. In a hydraulic machine, a rotor, means for producing a vortex of liquid at the inlet side of said rotor, means forming a sealed chamber segregated from said rotor, and air extraction conduit means connecting said chamber directly with the central portion of said vortex.

In testimony whereof, the signature of the inventor is affixed hereto.

FORREST NAGLER.
